UNITED STATES PATENT OFFICE.

JOSEPH C. GITHENS, OF NEW YORK, N. Y., ASSIGNOR TO THE RAND DRILL COMPANY, OF SAME PLACE.

ROTATORY FEED FOR STEAM ROCK-DRILLS.

SPECIFICATION forming part of Letters Patent No. 312,347, dated February 17, 1885.

Application filed May 2, 1884. (No model.)

To all whom it may concern:

Be it known that I, JOSEPH C. GITHENS, of the city and State of New York, have invented a certain Improvement in Rolling 5 Stops for Governing the Rotatory Feed of Steam Rock-Drills and Analogous Engines, of which the following is a specification.

This improvement is a modification of that described in my pending application for a 10 patent serially numbered 118,180, filed January 21, 1884, in which is described the employment of rollers, which are interposed between the wall of a chamber formed in the head of the steam-cylinder and the bottom of a 15 notch formed in a wheel or hub affixed to the end of the spiral bar which extends into the cylinder and enters the longitudinal recess formed in the piston, and imparts the rotatory feed to the piston by being held stationary 20 during the return-stroke of the piston, the rotatory set being imparted to the spiral bar during the working-stroke of the piston.

In order to avoid loss of time in effecting 25 the movement of the cylindrical stops from the wider parts of the recesses in which they are deposited to those parts of the recesses at which they bring up, expanding springs are employed, tending to press the rolling stops toward the narrower parts of the recesses.

30 The conditions precedent to the operation of the rolling stops are that there shall be a want of parallelism between the opposite side walls of the recesses in which the rollers are deposited, so that the turning of the spiral bar during the working-stroke of the piston 35 would have the effect of causing the rolling stops to roll toward the wider parts of the recesses in which they are deposited, while during the return-stroke of the piston the tendency of the spiral bar to turn in the opposite direction will so act upon the rollers as to cause them to roll toward the narrower parts of the recesses in which they are respectively deposited, by which tendency the rollers are 40 made to jam between the perimeter of the head of the spiral bar which constitutes one wall of the recess in which they are deposited and the opposite portion of the surface of the chamber in the head of the cylinder 45 which constitutes the other wall of the recess.

In order to keep the rollers in position to

jam instantly upon the commencement of the working-stroke of the piston, an expanding spiral spring is employed for each roller, which tends to press it toward the narrower 55 part of its recess, and thus hold it in contact with the wall of the chamber in the cylinder on one side and the periphery of the head of the spiral bar on the other side. When the spiral bar is rotated during the return-stroke 60 of the piston, these springs yield, and thus allow the rollers to move a sufficient distance toward the wider ends of their recesses and release the head of the spiral bar from friction.

In the structure shown in my application 65 serially numbered 118,180 the necessary tapering or want of parallelism of the opposed side walls of the recesses in which the rollers are deposited is obtained by making the bottoms of the notches in the head of the spiral 70 bar eccentric with relation to the circular wall of the chamber in the head of the cylinder in which the head or wheel on the end of the spiral bar is contained.

The modification which forms the subject of 75 my present invention consists in the employment of the cylindrical head of the spiral bar in combination with rollers contained in recesses formed in the side wall of the chamber in the head of the cylinder, the bottoms 80 of such recesses being eccentric with relation to the periphery of the head of the spiral bar.

In the structure shown in my application 85 No. 118,180 the eccentric bearing for the rolling stop was convex. In the present case the eccentric bearing, as will be seen, is concave, the concentric bearing being the periphery of the head of the spiral bar.

As the construction of rock-drills and analogous engines of the general character of that to which my present invention relates is well known, I do not deem it necessary to describe such construction in detail.

The accompanying drawing represents a 95 transverse section of the hub of a rock-drill cylinder containing my invention. The head of the cylinder A has cast upon it the usual ear, B, provided with the hole b, to receive the screw for effecting the longitudinal adjustment of the cylinder, and with the ears C and D, provided with the holes c and d, respect- 100

ively, for the reception of the bolts by which the heads of the cylinder are secured in position. The spiral bar E is keyed to or formed in one piece with the wheel or head F, 5 which is contained in the usual chamber, G, formed in the head of the cylinder. The bottom of this chamber is centrally perforated, as usual, for the admission of the spiral bar. In the wall of the chamber formed in the head 10 of the cylinder are provided a suitable number of recesses, G', the bottoms *g* of which are, as will be seen, eccentric with relation to the periphery of the head F. The cylindrical rollers or rolling stops H are deposited, respectively, in the recesses G', and, as shown, 15 are of slightly less diameter than the widest portion of those recesses. The rollers are pressed toward the narrower parts of those spaces by the expanding spiral springs h, 20 which are contained in suitable recesses formed in the head of the cylinder, and exert their expanding thrust upon the rollers H, respectively, thus tending to hold the rollers against the periphery of the head F.

25 By a consideration of the drawing it will be seen that if the spiral bar E turns in the direction indicated by the arrow motions will be imparted to the rollers H tending to roll them toward the wider parts of the space in 30 which they are contained and to compress the expanding springs h. It will also be understood that the extent of this rolling motion of

the rollers H will be just sufficient to cause them to release their grip upon the head F, and that as soon as there is any tendency of 35 the spiral bar E to rotate in the opposite direction such tendency would tend to cause the rollers H to roll toward the narrower parts of their recesses, and will hence cause them to instantly jam toward the eccentric wall G of 40 the recess and the periphery *f* of the head F. This organization subserves the same purpose as the organization shown in my application No. 118,180—that is, the extent of the rotatory feed of the piston is definitely varied after different working-strokes proportionately to any variations which there may have been in the length of such working-strokes. 45

I claim as my invention—

In mechanism for effecting the rotatory feed 50 of the piston in the cylinder of a steam rock-drill or other analogous engine, the side wall of the chamber formed in the head of the steam-cylinder, and provided with the concave recesses G', having their bottoms *g* eccentric with the periphery of the spiral bar, in combination with the rollers H and the head F of the spiral bar E, and the piston I, substantially as and for the purpose set forth. 55

JOSEPH C. GITHENS.
